DANGER SIGNAL FOR BRIDGES

Clarence Willan Waldahl, Fort Worth, Tex.

Application March 19, 1940, Serial No. 324,861

3 Claims. (Cl. 116—118)

This invention aims to provide a novel means whereby, when there is high water at a bridge, either a railroad bridge or a highway bridge, a signal will be given, admonishing train operators, the drivers of vehicles, and pedestrians, that dangerously high water exists.

It is within the province of the disclosure to improve generally and to enhance the utility of devices of that type to which the present invention pertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows, in vertical section, a device constructed in accordance with the invention, the parts being in the positions which they will assume when the device is set and when dangerously high water conditions do not exist;

Fig. 2 is a view similar to Fig. 1, but showing the parts in the positions which they will assume after the water has risen, and after the signal has been put into operation;

Fig. 3 is a section on the line 3—3 of Fig. 2.

The letter S indicates any suitable means for supporting a casing 1 adjacent to a bridge, in such position that when the water W rises to a dangerous stage, the casing 1 will be subjected to the rising water.

A partition 2 extends across the casing 1 from side to side, and across the casing from top to bottom. Intermediate its upper and lower edges, the partition 2 is supplied with an offset 3. The partition 2 defines a tank 4 in one end of the casing 1. In the opposite end of the casing 1 is secured an inverted L-shaped partition 5, extended across the casing from side to side, but of less height than the partition 2. The partitions 2 and 5 form, in one end of the casing 1, a water tight compartment 6 for certain operating instrumentalities which will be alluded to hereinafter. On the bottom of the casing 1 is fixed a nipple 7, communicating with the space between the partitions 2 and 5, the nipple being closed by a cap 8. The nipple 7 and the cap 8 afford access to the compartment 6, should such access be necessary or desirable.

A partition 9 extends across the casing 1, from

side to side, and is supplied at its lower edge with an angularly disposed stop flange 10. The partition 9 extends downwardly from the top of the casing 1 but terminates opposite to the upper portion of the offset 3 in the partition 2.

The partition 9 and the upper portion of the partition 2 form a receptacle 11 in the casing 1, access to the receptacle being possible, because the top of the casing 1 carries a moveable, water tight lid 12. Between the stop flange 10 of the partition 9 and the offset 3 of the partition 2, there exists an opening 14 in the bottom of the receptacle 11. The receptacle 11 is adapted to contain solid material 15, which is readily soluble in water, the material 15 being supported on a closure 19 for the opening 14, the closure being an element which will be described more fully hereinafter. In order to hold the solid, soluble material 15 in place, on the closure 19, and to prevent the receptacle 11 from having an unnecessary capacity, a triangular filler 16 is secured in the upper, inner angle of the receptacle 11, against the partition 9 and the top of the casing 1.

25 A guide tube 17, of any desired length, is secured at 18 in the top of the casing 1, and extends downwardly into the compartment 6, adjacent to the upper portion of the partition 2. The closure 19 (hereinbefore alluded to) is hingedly mounted at 20 in the upper part of the offset 3 of the partition 2, the closure having a rectangular arm 21, projecting into the compartment 6, below the guide tube 17. The offset 3 in the partition 2 is for the reception of the arm 21 of the closure or trigger 19, when the arm is in the position delineated in Fig. 2.

In the bottom of the casing 1, there is an inlet opening 22, communicating with the tank 4. The opening 22 is surrounded by a resilient, annular seat 23, adapted to receive a valve 24, pivotally mounted on a vertically movable radius rod 25, hingedly mounted on the bottom of the casing 1. When the water is below the bottom of the casing 1, the valve 24 cooperates with the seat 23 and closes the inlet opening 22. Thus, moisture is prevented from entering the empty tank 4 and finding its way to the solid soluble material 15, to the deterioration of that material. The valve 24, however, is somewhat buoyant, and when the water W enters the tank 4, as shown in Fig. 2 the valve tends to open, as in Fig. 2, thereby facilitating the entrance of the water into the tank 4.

A weight 26, preferably a rod, is mounted for reciprocation in the guide tube 17, and to the

upper end of the weight 26, a flexible element 27 is attached.

The flexible element 27 may be used to operate a signal of any desired kind, such as a block signal (not shown), but since any sort of signals may be used, the simple signal next to be described may be taken as typical of any preferred signal.

The signal may include a box-like body 28, provided with ventilating openings 29. The signal is so placed that it can be seen by pedestrians, the drivers of automobiles, or the operators of trains approaching a bridge. On its opposite sides and near its lower end, the body 28 of the signal is supplied with green bulls eyes 30, and above the bulls eyes 30, the body of the signal carries red bulls eyes 31, the colors of the signals 30 and 31 being, of course, a matter of selection.

A cage 32 is mounted for reciprocation, vertically, in the body 28 of the signal. The cage 32 is supplied with a lamp 33 of any desired construction. The lamp may be a simple lantern, supported on the bottom of the cage 2, and prevented from overturning by engaging the bail of the lantern with a hook 34 on the upper part of the cage.

The flexible element 27 enters the body 28 of the signal slidably, the cage 32 being slideable on one run of the flexible element. The flexible element 27 is rove over direction-changing idlers 35 mounted on the upper part of the body 28, and one end of the flexible element is connected at 36 to the top of the cage 32.

Assuming that the device is set, as shown in Fig. 1, the solid soluble material 15 is supported on the closure 19, and the arm 21 of the closure extends into the compartment 6, and supports the rod 26 in an elevated position, the cage 32 being lowered until the lantern 33 or its equivalent shines through the green bulls eyes 30, a safety signal thus being afforded.

If, however, water in the stream rises, as shown at W in Fig. 2, the water enters the tank 4 by way of the opening 22. The closure 19 does not stop the opening 14 hermetically, and the water finds its way into the receptacle 11, dissolving away the retainer 15. The leaky closure 19 is released, the arm 21 of the closure is per-

mitted to swing downwardly, and the weight or rod 26 moves downwardly, the flexible element 27 raising the cage 32, until the lantern 33 shines through the red bull's eyes 31, and affords a danger signal.

5 The device is simple in construction, but will be found thoroughly advantageous for affording a signal in the event of rising water beneath a bridge or other structure.

Having thus described the invention, what is

10 claimed is:

1. In a device for indicating rising water, a casing having a partition defining a tank and a compartment, the casing having a water inlet for the tank, a receptacle in the tank and having an opening in its bottom, a leaky closure for the opening, hingedly mounted on the partition, the closure including an arm extended into the compartment, a weight movable in the compartment, a signal operatively connected with the weight, and material in the receptacle, said material being soluble in water and resting on the closure, to maintain the arm in the path of the downward movement of the weight.

2. In a device for indicating rising water, a 25 receptacle having an opening in its bottom, a leaky closure for the opening, hingedly mounted on one wall of the receptacle, the closure including an arm extended out of the receptacle, a weight movable externally of the receptacle, a 30 signal operatively connected with the weight, and material in the receptacle, said material being soluble in water and resting on the closure, to maintain the arm in the path of the downward movement of the weight.

3. In a device for indicating rising water, a 35 signal, actuating means for the signal, a movably-mounted trigger cooperating with the actuating means to hold it in inoperative position, a retainer on the trigger and acting on the trigger by gravity, and counter to the actuating means, to cause the trigger to maintain the actuating means in inoperative position, and means for supporting the device in such position that the retainer is accessible to rising water, the retainer being soluble in water, to reduce the weight on the trigger.

CLARENCE WILLAN WALDAHL.
